UNITED STATES PATENT OFFICE.

THOMAS HODGES, THOMAS ROBERT WILLIAM HODGES, AND REGINALD HODGES, OF CALLESTICK, ENGLAND.

APPARATUS FOR RAISING AND LOCATING SUBMERGED VESSELS.

Application filed July 7, 1926, Serial No. 121,009, and in Great Britain March 23, 1926.

This invention relates to improvements in means for locating sunken vessels and raising same. The apparatus is of the kind in which locating buoys are released from a sinking ship and rise to the surface when the vessel sinks each of the buoys being connected to the sunken ship by a cable. A rescuing or salvaging ship picks up the cable attached to each buoy and passes a shackle 10 or the like down the cable which automatically secures itself to the sunken vessel. Each shackle carries a lifting hawser by which the vessel may be raised.

According to our invention a vessel is provided with two or more buoys which are normally held on seatings on the vessel's deck. Each buoy is constructed with a central recess underneath, which fits over a bollard or like fitting when in place on the deck.

From the underside of each buoy extends downward a short rod or shaft which passes through a central tube in the bollard and through the deck where it is secured on the underside by a nut. When the buoy is released to float to the surface it will carry with it one end of a cable, the other end being permanently attached to the ship. The releasing of the buoy is arranged to also release and raise a normally collapsed mast carried on the buoy. As the mast moves to an upright position it is caused to tear off the seal of a calcium light canister which will thus provide a light on the buoy when it reaches the surface.

When a cable connecting a buoy is picked up, a shackle or the like, carrying a lifting hawser, is placed thereon when it will drop down the cable. The shackle is provided with means whereby it will lock itself to the bollard when it drops on the same.

In a preferred embodiment of our invention the bollard is mounted in a gimbal bearing on the deck so that it can assume a vertical position should the vessel be lying at an angle. The bollard is provided with four or more radial arms hinged to the body of the same. These arms are provided with hooked shaped ends and are forced outwardly by suitably arranged springs. Extensions from the arms are arranged to engage against a ring or the like on the bollard and limit their outward movement.

The shackle which slides down the buoy cable and engages over the bollards may

consist of a central tubular member through which the cable passes and a frame connected by spider arms formed with a ring at its lower end. When the shackle falls on the bollard the shackle ring will force in the 60 spring pressed arms on the bollard and after passing same the said arms will be able to move out again and thus lock the shackle to the bollard. The shackle where it engages on the top of the bollard may be provided with a number of triangular or other shaped projections which will engage similar shape projections on the top of the bollard thus ensuring that the shackle ring correctly engages the bollard arms. 65

The buoy, before release, may be provided with a watertight seating on the vessel's deck. The short rod or shaft from the buoy passing through the bollard and deck, is preferably jointed so as to be relieved of strain 70 should the buoy have much movement through a heavy sea and when it reaches the surface. The lower end of this rod from the buoy is threaded to receive a securing nut. The top portion of the nut may be 75 formed as a cylindrical boss on which is mounted a sleeve having a pair of trunnions. These trunnions are adapted to be engaged by the forked ends of a pivoted lever the opposite end being connected to a stout coil 80 spring. To this last mentioned end of the pivoted lever is also connected a series of links which pass through the deck of the vessel and up to the top of the buoy. 85

On the top of the buoy is mounted a telescopic mast which is arranged to be normally held down horizontally on the buoy by the top link of the above mentioned links. 90

This link may be arranged to engage in a slot provided in the top section of the telescopic mast and cause the release of a flag contained therein as the mast is released. 95

When the mast is released by the withdrawal of the links caused by the movement of the pivoted arm engaging the sleeve on the buoy rod, the mast is caused to swing up to a vertical position and the telescopic sections opened out by spring means. 100

The mast in its horizontal position is attached to the seal of a calcium light canister 105 so that as the mast is raised the canister will be opened and will thus produce a light on the buoy when it reaches the surface. The buoy may be provided around its circumference at or the top with spaced eye bolts 110

in which are hung a life line or lines for the use of any survivors in the water.

In order that our invention may be clearly understood and readily carried into effect we have appended hereto three sheets of drawings illustrating an embodiment of same wherein:—

Fig. 1 is a sectional elevation showing a buoy and its associated parts in position on a vessel.

Fig. 2 shows a buoy released.

Fig. 3 shows in elevation a shackle for lowering down the buoy cable and for engagement with the bollard.

Fig. 4 is a plan view of the shackle.

Fig. 5 is an elevation view having the shackle engaged over the bollard.

Fig. 6 is a view illustrating the mechanism for automatically releasing a device for indicating that the shackle is properly engaged with the bollard, and

Fig. 7 is a sectional detail view of part of this mechanism.

Referring to the drawings the buoy 1 is a hollow cylindrical metal body having a concentric space 2 open at the bottom. The buoy may be strengthened by internal webs or stays to enable it to withstand the pressure of water at certain depths. The space 2 accommodates the upper end of a bollard 3 secured to the vessel. The annular base 4 of the buoy 1 rests upon a circular bracket 5 having a rubber strip 6.

The bollard 3 is provided with a central bore 7 to receive a rod 8 the upper end of which is connected to a coupling member 9 secured to the buoy at a point on the axis of the buoy. The rod 8 is preferably connected to the member 9 in a universal manner as indicated at 10 to allow the buoy to move readily relative to the rod 8 when the buoy is released and riding on the surface of the water. The lower end of the rod 8 is apertured, as indicated at 11, to receive a suitable cable, and a thread 12 is provided on the lower end of the rod 8 to receive a nut 13 which holds the rod 8, and consequently the buoy 1, in position on the vessel. The buoy is released by unscrewing the nut 13.

The unscrewing of the nut 13 brings into vertical position upon the top of the buoy a mast 14, which normally assumes the position shown in Fig. 1. This mast is formed of telescopic units which open out to their full extent automatically when the mast is released to assume the vertical position. This automatic extension of this mast can be effected by providing a coiled spring 15 inside the mast, such coiled spring being held under compression by pressing in the free end of the mast and engaging such free end of the mast or some other convenient part of the mast with an abutment when it is in the folded position. The mechanism for releasing the mast and bringing

it to the vertical position consists of a coiled spring 16 which is normally extended so that it has a tendency to contract and pull downwards the lower end of the mast 14 which is pivotally supported between a pair of brackets 17. The lower end of the mast engages a movable abutment, 18, which is in the form of a cranked lever 19 fulcrumed at 20, and having a pin and slot connection 21 with a rod 22 which extends downwards and is pivotally connected to a rod 23 slideable through a sleeve or bush 24 secured to the vessel, the lower end of the rod 23 being pivotally connected by a link 25 to a horizontal arm 26.

The arm 26 is pivotally supported by a fixed pivot pin 27 engaging in a slot 28 intermediate the ends of the arm. One end of the arm 26 is forked as at 29 to receive a lateral projection 30 carried by a collar 31 which is carried by the nut 13 but is held stationary during the rotation of the nut with a consequent movement of the arm 26 against the influence of a coiled spring 32.

The bollard 3 is mounted in a gimbal bearing on the deck so that it can be held in a vertical position when the vessel assumes a position at an angle to its normal horizontal position. For this purpose a pair of bearing blocks 33 are provided upon diametrically opposite sides of the bollard and supported in these blocks is a member 34 free to rotate axially in the blocks 33 and having a collar-like central portion 35 surrounding the bollard which is supported by a pair of lateral pins 36 extending from the bollard and rotatably supported in the collar 35.

The bollard is provided with a number of radial arms 37 pivotally supported in a suitably strong manner, for instance as indicated at 38, whereby they can move inwards against the influence of coiled springs 39. The arms 37 are prevented from moving outwards beyond a predetermined point by an annular ring 40 carried by the bollard, by means of radial brackets 41 integral with the bollard. The arms 37 are formed with hook-shaped portions 41 under which is adapted to be engaged the ring-like base 42 of a shackle 43 (see Figs. 3, 4 and 5), such shackle 43 being lowered down the cable to which the buoy 1 is attached, when the buoy is released, whereby the shackle 43 slips over the top of the bollard, and by reason of its weight forces the arms 37 inwards, such arms returning to their normal position when the ring 42 of the shackle passes them so that they provide abutments for the base of the shackle when the hawser 44 carrying the shackle is pulled taut by the raising mechanism.

To indicate to the salvage party that the shackle 35 is properly engaged with the bollard, a buoyant object 45 is released automatically consequent upon the engagement

of the ring 42 with the arms 37. This can be effected by providing just beneath one of the hooks 41 of one of the arms 37 a link 46 pivotally supported at one end 47 and lying across a point where it will be engaged by the ring 42 of the shackle 43, whereby the link 46 is moved inwards with a consequent retraction of a slid able rod 48 against which the buoyant object 45 is free to rise to the surface of the water. The transmission of the movement of the link 47 to the rod 48 is by means of a series of links 49 which operate to raise a depending rod 50 thereby enabling a compressed coiled spring 51 to come into operation and move towards the bollard a rod 52 connected universally as at 53 to the rod 48. The rod 52 and the spring 51 operate in a tubular portion of the gimbal element 34.

20 To correctly position the shackle 43 upon the bollard, the top of the bollard is provided with a truncated conical extension 54 the upper end of which is formed with angular recesses 55 to receive triangular projections 56 depending from the collar 57 constituting the upper end of the shackle. Spiders 58 connect the collar 57 to the ring 42.

30 The buoy 1 may have cables 59 secured around it by which survivors in the water can hold on. Suitable calcium flares, or other illuminating means may be provided with the buoy 1 and the buoyant body 45.

35 The apparatus employed by our invention may be of various sizes according to the size of ship to which they are fitted and information as to the size used may be painted on the buoy and flag so that a salvaging ship will know what size shackle to employ. For a small vessel such as a tug or submarine a bollard and buoy may be fitted at each end of the same, for larger vessels additional sets of buoys and their attendant parts will be required.

40 We claim:—

1. Apparatus for raising and locating submerged vessels comprising two or more bollards secured upon the vessel, floats normally located over said bollards, means for releasing said floats, a cable or its equivalent attached to each float, said cable being adapted to be utilized as a guide for lowering a shackle member into engagement with said bollard, means whereby the shackle can automatically be coupled to said bollard to enable a hawser or the like connected to the shackle to be utilized for raising the vessel, said float having a vertical rod attached to its vertical axis and passing through said bollard, means being provided for engagement with said rod for holding the float in position and for releasing same.

2. Apparatus for raising and locating submerged vessels, comprising two or more bollards secured upon the vessel, floats nor-

mally located over said bollards, means for releasing said floats, a cable or its equivalent attached to each float, said cable being adapted to be utilized as a guide for lowering a shackle member into engagement with said bollard, means whereby the shackle can automatically be coupled to said bollard to enable a hawser or the like connected to the shackle to be utilized for raising the vessel, said float having a vertical rod attached to its vertical axis and passing through said bollard, means being provided for engagement with said rod for holding the float in position and for releasing same, said means for engagement with said rod for holding the float in position being adapted to operate, simultaneous with the releasing of the float, mechanism for automatically releasing to a vertical position a mast normally horizontally disposed upon said float.

3. Apparatus for raising and locating submerged vessels, comprising two or more bollards secured upon the vessel, floats normally located over said bollards, means for releasing said floats, a cable or its equivalent attached to each float, said cable being adapted to be utilized as a guide for lowering a shackle member into engagement with said bollard, means whereby the shackle can automatically be coupled to said bollard to enable a hawser or the like connected to the shackle to be utilized for raising the vessel, said float having a vertical rod attached to its vertical axis and passing through said bollard, means being provided for engagement with said rod for holding the float in position and for releasing same, said means for engagement with said rod for holding the float in position being adapted to operate, simultaneously with the releasing of the float, mechanism for automatically releasing to a vertical position a mast normally horizontally disposed upon said float, the said rod connected to the float having a nut threaded on to its lower end, such nut being adapted to be unscrewed from the rod to release the float, the movement of such nut being adapted to impart movement to a lever connected by links to a movable abutment engaging part of said mast, a coiled spring normally under tension being connected to said mast for raising it to a vertical position when said abutment is moved away from the mast.

4. Apparatus for raising and locating submerged vessels, comprising two or more bollards secured upon the vessel, floats normally located over said bollards, means for releasing said floats, a cable or its equivalent attached to each float, said cable being adapted to be utilized as a guide for lowering a shackle member into engagement with said bollard, means whereby the shackle can automatically be coupled to said bollard to enable a hawser or the like connected to the

shackle to be utilized for raising the vessel, each said shackle comprising a ring-like base connected by vertical spiders to a common element adapted to receive a hawser, said shackle being adapted to receive the cable to which the float is connected whereby the shackle can slide down the said cable and be engaged with the bollard.

5. Apparatus for raising and locating submerged vessels comprising two or more bollards secured upon the vessel, floats each comprising a hollow body having a concentric recess to receive the upper end of a bollard, a cable attached to each float, said cable being adapted to be utilized as a guide for lowering a shackle member into engagement with a bollard, means whereby the shackle can be automatically coupled to said bollard to enable a hawser or chain connected to the shackle to be utilized for raising the vessel, each said shackle comprising a ring like base connected by vertical spiders to a common element adapted to receive a hawser, said shackle being adapted to receive the cable to which the float is connected whereby the shackle can slide down the said cable and be engaged with the bollard.

6. Apparatus for raising and locating submerged vessels comprising two or more bollards secured upon the vessel, floats each comprising a hollow body having a concentric recess to receive the upper end of a bollard, a cable attached to each float, said cable being adapted to be utilized as a guide for lowering a shackle member into engagement with a bollard, means whereby the shackle can be automatically coupled to said bollard to enable a hawser or chain connected to the shackle to be utilized for raising the vessel, each said shackle comprising a ring like base connected by vertical spiders to a common element adapted to receive a hawser, said shackle being adapted to receive the cable to which the float is connected whereby the shackle can slide down the said cable and be engaged with the bollard, said bollard having a number of substantially hook shaped radial arms held in a position extending from the bollard by springs, the said shackle being adapted to slip off said arms so as to be engaged under them when tension is applied to the hawser connected to the shackle.

7. Apparatus for raising and locating submerged vessels comprising two or more bollards secured upon the vessel, floats each comprising a hollow body having a concentric recess to receive the upper end of a bollard, a cable attached to each float, said cable being adapted to be utilized as a guide for lowering a shackle member into engagement with a bollard, means whereby the shackle can be automatically coupled to said bollard to enable a hawser or chain con-

nected to the shackle to be utilized for raising the vessel, each said shackle comprising a ring like base connected by vertical spiders to a common element adapted to receive a hawser, said shackle being adapted to receive the cable to which the float is connected whereby the shackle can slide down the said cable and be engaged with the bollard, the shackle and the upper end of the bollard having substantially triangular 70 projections and recesses which co-operate to correctly align the shackle upon the bollard.

8. Apparatus for raising and locating submerged vessels, comprising two or more bollards secured upon the vessel, floats normally located over said bollards, means for releasing said floats, a cable or its equivalent attached to each float, said cable being adapted to be utilized as a guide for lowering a shackle member into engagement with 85 said bollard, means whereby the shackle can automatically be coupled to said bollard to enable a hawser or the like connected to the shackle to be utilized for raising the vessel, each said shackle comprising a ring like 90 base connected by vertical spiders to a common element adapted to receive a hawser, said shackle being adapted to receive the cable to which the float is connected whereby the shackle can slide down the said cable 95 and be engaged with the bollard, the bollards being supported by gimbals which allow for a substantial universal movement of the bollard.

9. Apparatus for the location and raising of submerged vessels comprising two or more bollards secured upon the vessel, floats normally located over said bollards, means for releasing said floats, a cable or its equivalent attached to each float, said 105 cable being adapted to be utilized as a guide for lowering a shackle member into engagement with said bollards, means whereby the shackle can automatically be coupled to said bollard to enable a hawser or the like connected to the shackle to be utilized for raising the vessel, means being provided for automatically releasing a buoyant object consequent upon the correct engagement of the shackle with the bollard, substantially 110 as and for the purpose described.

10. Apparatus for raising and locating submerged vessels, comprising two or more bollards secured upon the vessel, floats normally located over said bollards, means for 120 releasing said floats, a cable or its equivalent attached to each float, said cable being adapted to be utilized as a guide for lowering a shackle member into engagement with said bollard, means whereby the shackle can automatically be coupled to said bollard to enable a hawser or the like connected to the shackle to be utilized for raising the vessel, each said shackle comprising a ring like 125 base connected by vertical spiders to a com- 130

mon element adapted to receive a hawser, said shackle being adapted to receive the cable to which the float is connected whereby the shackle can slide down the said cable 5 and be engaged with the bollard, means being provided for automatically releasing a buoyant object consequent upon the correct engagement of the shackle with the bollard, substantially as and for the purpose described.

11. Apparatus for raising and locating submerged vessels, comprising two or more bollards secured upon the vessel, floats normally located over said bollards; means for 15 releasing said floats, a cable or its equivalent attached to each float, said cable being adapted to be utilized as a guide for lowering a shackle member into engagement with said bollard, means whereby the shackle can 20 automatically be coupled to said bollard to enable a hawser or the like connected to the shackle to be utilized for raising the vessel, each said shackle comprising a ring like base connected by vertical spiders to a 25 common element adapted to receive a hawser, said shackle being adapted to receive the cable to which the float is connected whereby the shackle can slide down the said cable and be engaged with the bollard, the 30 bollards being supported by gimbals which allow for a substantial universal movement

of the bollard, means being provided for automatically releasing a buoyant object consequent upon the correct engagement of the shackle with the bollard, substantially as 35 and for the purpose described.

12. Apparatus for raising and locating submerged vessels, comprising two or more bollards secured upon the vessel, floats normally located over said bollards, means for 40 releasing said floats, a cable or its equivalent attached to each float, said cable being adapted to be utilized as a guide for lowering a shackle member into engagement with said bollard, means whereby the shackle can 45 automatically be coupled to said bollard to enable a hawser or the like connected to the shackle to be utilized for raising the vessel, said float having a vertical rod attached to its vertical axis and passing 50 through said bollard, means being provided for engagement with said rod for holding the float in position and for releasing same, means being provided for automatically 55 releasing a buoyant object consequent upon the correct engagement of the shackle with the bollard, substantially as and for the purpose described.
